Primary Examiner — Vy N Koenig*Assistant Examiner* — Qiawen W Wiechert(74) *Attorney, Agent, or Firm* — Andrew C. Cheng(57) **CLAIM**

The ornamental design for the kids travel tray as shown and described.

DESCRIPTION

FIG. 1 is a top, front, right perspective view of a kids travel tray of my new design;

FIG. 2 is a bottom, rear, left side perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is a perspective view of the kids travel tray of FIG. 1, shown in an alternate configuration; and,

FIG. 10 is a perspective view of the kids travel tray of FIG. 1, shown in another alternate configuration.

The broken lines in the figures depict portions of the kids travel tray that form no part of the claimed design.

1 Claim, 10 Drawing Sheets(56)
